UNITED STATES PATENT OFFICE.

EDMUND DALGLEISH, OF LAKWOOD, OHIO, ASSIGNOR TO THE CHASE MACHINE COMPANY, OF CLEVELAND, OHIO, A CORPORATION OF OHIO.

BOTTLE-HANDLING APPARATUS.

1,110,256.

Specification of Letters Patent.

Patented Sept. 8, 1914.

Application filed November 17, 1913. Serial No. 801,437.

To all whom it may concern:

Be it known that I, EDMUND DALGLEISH, a citizen of the United States of America, residing at Lakewood, in the county of Cuyahoga and State of Ohio, have invented certain new and useful Improvements in Bottle-Handling Apparatus; and I hereby declare the following to be a full, clear, and exact description of the invention, such as will enable others skilled in the art to which it pertains to make and use the same.

This invention relates to new and improved bottle-handling apparatus and particularly to apparatus for transferring bottles from one crate to another and inverting them in the process of transferring them.

One object of this invention is to provide an apparatus of this character which can be easily operated and which will quickly transfer the bottles from one crate to another crate without chipping or breaking the bottles and which will eliminate any necessity of the operator touching the bottles with his hands, thereby minimizing the liability of the bottles being contaminated during the transferring process.

With this object in view and with the intention of securing other advantages which will hereinafter appear my invention consists in the features of construction and combination of parts, hereinafter described in the specification, pointed out in the claims and illustrated in the accompanying drawings.

Figure 1 is a top plan of the machine embodying my invention. Fig. 2 is a section on line 2—2, Fig. 1. Fig. 3 is a section on line 3—3, Fig. 1. Fig. 4 is a section on line 4—4, Fig. 2, looking in the direction of the arrow. Fig. 5 is a section on line 5—5, Fig. 2, looking in the direction of the arrow.

By referring to the drawings it will be seen that my improved machine comprises in general a main frame and a rotatable frame mounted in and supported by said main frame. The main frame comprises a bed or table 1 having vertically arranged side members or standards 2 which extend up from each side of the table near the center thereof. In the top of the bed or table is formed an oblong opening 3. On the inner face of each of the said standards 2 is arranged an annular track 5 and on the outer surface of said track 5 are arranged a series of pins 6 which form a segmental gear

which extends around somewhat less than a quarter of the circumference of the said track 5. Near the center of each standard 2, on the inner face thereof, is arranged a circular groove or guideway 7 and this guideway communicates toward the base of the standard with a straight vertically arranged guideway 8, the two guideways forming what might be termed a cam groove.

On the top of the table at each end thereof are mounted tracks 9, which extend from the side edges of the said standards 2 to beyond the ends of the said table. These tracks are angle shaped in cross-section and are spaced a sufficient distance apart to support and guide a bottle-holding crate.

It may be here stated that the bottle crates used in the machine are of the type now in common use and in the drawings one bottle crate is shown in the lower part of the rotatable frame right side up and containing bottles and another crate is shown inverted in the upper part of the rotatable frame. Each crate comprises side members *a* generally of wood and a bottom formed of a series of parallel wires *b*. Other wires *c* are arranged a distance above the bottom to further position the bottles.

The rotatable frame comprises a bottle guiding frame and two crate-carrying frames. The three frames are operatively connected so that they can be partially rotated as one frame. In the position of the machine shown in the drawings one crate-carrying frame occupies a position below the bottle guiding frame and the other crate-carrying frame occupies a position above the bottle-guiding frame and the upper crate-carrying frame is inverted, but when the rotatable frame is turned through half a revolution the position of the crate-carrying frames will of course be reversed.

The bottle-guiding frame comprises a rectangular frame 15 which in cross-section corresponds in size and shape to a cross-section of a bottle-crate. Within the said frame 15 are arranged guide members 16 of suitable shape and construction for dividing the interior of the frame into as many separate passageways or guideways as there are bottles in a crate.

On opposite sides of the bottle-guiding frame adjacent to the standards 2 are formed lugs 17. Each lug 17 carries a head 18 and to said head 18 is bolted a plate 19 which

carries a trunnion 20. Each trunnion 20 extends into a bearing 21 on the adjacent standard 2, the said bearing being arranged at the center of the circular guideway 7. Each trunnion is preferably provided with a shoulder which abuts against the bearing 21 and prevents the lateral shifting of the trunnion. Each plate 19 carries a pair of oppositely extending arms or guide-bars 24 which extend parallel with the said standards 2. The purpose of said guide-bars will appear later.

The crate-carrying frames are identical in construction and each crate-carrying frame 15 comprises a pair of tracks 26 which are spaced the same distance apart as the tracks 9 and the tracks 26 of the crate-carrying frames are arranged to register with said tracks 9 when said crate-carrying frames are 20 in their lower position. The tracks 26 are provided with side flanges 27. Said tracks 26 are suitably secured together by cross-members 28 which form the tie pieces of the crate-carrying frame. At the side of each 25 of the tracks 26 at the center thereof is arranged a supporting arm 30 and near the upper end of said arm 30, at the outer side thereof is formed a boss 31 which carries a pin 32 on which is mounted a roller 33. In 30 the position of the machine shown in the drawings the rollers 33 on the arms 30 of the crate-carrying frame in the lower part of the rotatable frame extend into the straight guideways 8 on the standards 2 and 35 the rollers 33 on the arms 30 of the crate-carrying frame in the upper part of the rotatable frame extend into the circular guideways 7. When the rotatable frame is raised, as hereinafter described, the rollers on the 40 arms of the lower crate-carrying frame will travel up the said guideways 8 and enter the circular guideways 7. Then when the rotatable frame is turned the rollers on the arms of each crate-carrying frame will 45 travel around said circular guideways 7 and when the upper crate-carrying frame reaches the position formerly occupied by the lower crate-carrying frame, the rollers thereon will pass down into the straight guideways 50 8. In each of the arms 30 is formed a longitudinally extending slot 35 which is adapted to loosely receive one of the aforementioned guide bars 24. On the sides of the crate-carrying frames are arranged pins 37. 55 An operating lever 40 is pivotally mounted at its center on each of the trunnions 19 between the bottle-guiding frame and the standards 2. A pair of links 41 are pivotally connected to each lever 40, the said links being 60 connected at opposite sides of the center of said lever and one link extends up and the other link extends down. In the ends of said links 41 are formed slots 42 which are adapted to receive the pins 37 on the sides of 65 the crate-carrying frames. Each operating

lever 40 is provided at each end with a handle 44.

On the bottom of the tracks 26 on each of the crate-carrying frames are arranged bearings 50 which carry a horizontally arranged shaft 51 and on the end of said shaft 51 are secured rollers 52. The said rollers 52 are so located that when the lower crate-carrying frame is raised the rollers thereon will come in contact with said tracks 5. In the peripheries of the said rollers 52 are formed holes 53 which are adapted to receive the pins 6 which form the segmental gear on said tracks 5. The said bearings 50 support a cross-bar 55 which extends parallel with the shaft 51, but is spaced a short distance therefrom and on said cross-bar are arranged bosses 56 in which are formed square openings 57. Three of these bosses 56 are shown and each boss is located directly in line with a bottle in a bottle crate. In the holes or openings 57 in each of said bosses 56 is slidably arranged a push bar 59 which carries a rectangular shaped head 60 which is adapted to pass up between the wires which form the bottom of the crate and engage the bottom of a bottle therein. Each of the said push bars 59 carries a rack 61. Other push bars 63 having heads 64 are connected with the push bars 59 so that there is one push bar for each bottle in the crate. On the shaft 51 is secured a series of gear wheels 65 and each gear wheel is arranged to mesh with the rack on an adjacent push bar 59. When the said shaft 51 is rotated the gear wheels thereon will be driven and as said wheels are in engagement with the racks on the push bars 59 the said push bars 59 and the push bars 63 connected therewith will be shoved up into engagement with the bottoms of the bottles in the crates.

The operation of the device is as follows: An empty crate is placed inverted in the crate-carrying frame in the top part of the machine and a full crate is placed in the crate-carrying frame in the bottom of the machine. The operator then takes hold of the handle 44 on the lever 40 and turns the lever in the direction indicated by the arrow. On the first movement of the said lever the lower crate-carrying frame is raised bodily until the bottle crate therein is brought up against the bottle-guiding frame. On the further movement of the lever the rotatable frame will be swung around and as it moves the rollers 52 on the lower crate-carrying frame will engage with the segmental gear on the tracks 5 causing the shaft 51 to be rotated thereby rotating the gears thereon which are in mesh with the racks on the push bars so that the said push bars will engage with the bottles in the crate and shove said bottles through the bottle-guiding frame and into the empty crate. After the rotatable frame has completed a half revo-

lution the bottle-crate which occupied the top of the frame at the beginning of the operation will be at the bottom of the frame with the bottles therein but the bottles will 5 be inverted. The crate is then drawn out onto the tracks on the top of the table from whence it is lifted off and another full crate placed in the lower crate-carrying frame.

What I claim is—

- 10 1. In an apparatus of the character described, the combination of a stationary frame, a rotatable frame mounted on said stationary frame, a crate carrying frame arranged at each end of said rotatable frame, 15 said crate-carrying frames being oppositely disposed and means for rotating said rotatable frame.
2. In an apparatus of character described, the combination of a stationary frame, 20 a rotatable frame mounted in said stationary frame, said rotatable frame comprising a centrally arranged bottle guiding frame and a crate-carrying frame arranged at each side of said bottle-guiding frame and oppositely disposed, and means for rotating said rotatable frame.
3. In an apparatus of the character described, the combination of a stationary frame, a rotatable frame mounted in said stationary frame, said rotatable frame comprising a centrally arranged bottle-guiding frame and a pair of crate-receiving frames, the said crate-receiving frames being mounted at the ends of the said rotatable 35 frame and being oppositely disposed so that the tops of the said crate-receiving frames are adjacent to the said bottle guiding frame and means for engaging with and forcing the bottles in one crate through said bottle-guiding frame into the other crate.
4. In an apparatus of the character described, the combination of a stationary frame, said stationary frame being provided with standards, a track carried by 45 each standard, a rotatable frame mounted in each stationary frame, said rotatable frame comprising a bottle-guiding frame and two crate-carrying frames, said crate-carrying frames being oppositely disposed 50 and mounted at each side of the bottle-guiding frame and rollers mounted on said crate-carrying frame and adapted to have traction on the said tracks on the said standards.
5. In an apparatus of the character described, the combination of a stationary frame, said stationary frame being provided with standards, a circular guideway formed on the inner face of each of said 55 standards, a straight guideway communicating with each circular guideway near the base of the standard, a rotatable frame mounted between said standards, the bearings for said frame being arranged at the 60 centers of said circular guideways, said
- frame comprising a bottle-guiding frame and two oppositely disposed crate-carrying frames, rollers carried by said crate-carrying frames, the rollers on the upper crate-carrying frame extending into the said circular guideways and the rollers on the lower crate-carrying frame extending into the straight guideways, means for raising the lower crate-carrying frame so as to bring the rollers thereon into the circular guideways and means for rotating said rotatable frame. 70
6. In an apparatus of the character described, the combination of a stationary frame, said stationary frame being provided with standards, a circular guideway arranged on the inner face of each standard, and a straight guideway communicating with said circular guideway, a rotatable frame mounted between said standards, the axis of rotation of said frame being at the center of said circular guideway, said rotatable frame comprising a bottle guiding frame and a crate-carrying frame at each side of the bottle-guiding frame, said crate-carrying frames being free to slide toward and away from the bottle-guiding frame, operating levers mounted on the rotatable frame and links operatively connecting said levers with the crate-carrying frames so 95 that the operation of said levers will impart a vertical movement to the crate-carrying frame and a rotating movement to the rotatable frame. 90
7. In an apparatus of the character described, the combination of a stationary frame, said stationary frame being provided with standards, a segmental gear arranged on each standard, a rotatable frame mounted between said standards, said rotatable frame comprising a bottle-guiding frame and two oppositely disposed crate-carrying frames, bearings arranged on the bottoms of the crate-carrying frames, shafts mounted in the said bearings, rollers secured 100 on the ends of said shafts and adapted to engage with the segmental gears, push bars supported from the bottoms of said crate-carrying frames, racks carried by said push bars and gear wheels mounted on said shafts 110 and adapted to engage with the said racks 115 on said push bars, for the purpose set forth.
8. In an apparatus of the character described, the combination of a stationary frame, said stationary frame being provided with standards, a segmental gear mounted on each standard, a circular guideway arranged on each standard, straight guideways arranged near the base of said standards and communicating with said circular guideways, a rotatable frame mounted between said standards, said rotatable frame comprising a bottle guiding frame and two oppositely disposed crate-carrying frames, rollers mounted on said crate-carrying 125 frame. 130

frames, and adapted to extend into the circular guideways and into the straight guideways according to the position of said crate-carrying frames, shafts supported from the bottoms of said crate-carrying frames, rollers secured on said shafts and adapted to engage with the segmental gears, push bars slidably supported from the bottoms of the crate-carrying frames, racks carried by said 10 push bars and gears secured on said shafts

and adapted to engage with said racks, for the purpose set forth.

In testimony whereof, I sign the foregoing specification, in the presence of two witnesses.

EDMUND DALGLEISH.

Witnesses:
